UNITED STATES PATENT OFFICE.

CHARLES S. KNAPP, OF CHICAGO, ILLINOIS, ASSIGNOR TO JOSEPH W. WEINLAND, OF CHICAGO, ILLINOIS.

BRAKE-HEAD.

1,124,915.

Specification of Letters Patent.

Patented Jan. 12, 1915.

Application filed December 31, 1913. Serial No. 809,649.

To all whom it may concern:

Be it known that I, CHARLES S. KNAPP, a citizen of the United States, residing at Chicago, in the county of Cook, State of Illinois, have invented certain new and useful Improvements in Brake-Heads, of which the following is a specification.

My invention relates to railway cars, and has particular reference to a novel brake-head for use on brake beams.

Many forms of brake heads have been suggested wherein the head is adjustably held on the end of the brake-beam. In earlier patents constructions have been provided wherein the head is held in adjusted position by clamping a portion of the head tightly against the sleeve on the end of the beam. In other constructions, for instance, the patent to Fowler, No. 990,855, such construction is combined with wedge-means, whereby wedging force is exerted simultaneously with the clamping force. However, in any construction involving the use of a split head a certain disadvantage accrues in that if the brake shoe becomes broken transversely, a portion of the braking force is applied to the extreme ends of the brake head instead of being applied at the lugs near the center supported on the sleeve directly to the middle thereof. This exerts a force tending to break the head, which tendency can best be resisted by constructing the head with continuous bearing-portions around the sleeve, such bearing-portions being in the form of struts which complete the truss. In the split-head construction this strut is absent and the breakage occurs under the circumstances mentioned. I propose to obviate this difficulty and at the same time retain the advantageous construction of the Fowler patent referred to. That is, I provide in effect a split-head and a wedge-device, both of which are actuated by the same bolt, the sides of the brake-head at its point of bearing on the sleeve being circumferentially complete.

The invention will be more readily understood by reference to the accompanying drawings, wherein—

Figure 1 is a side-elevation of a brake-head constructed in accordance with my invention; Fig. 2 is a rear elevation of the same construction, and, Fig. 3 is a transverse-section on line 3—3 of Fig. 1.

Referring more particularly to the draw-

ings, it will be seen that I provide a sleeve 10 having concentric peripheral-grooves 11 therein, on which sleeve is mounted a brake-head 12 having circumferentially-complete bearing-portions 13. Thus, a rigid brake-head is formed, so constructed that should a brake-shoe become broken the braking-force will not tend to weaken the head due to unequally applied force. In order to further strengthen the body portion of the head I may provide ribs or struts 13a, extending between the rear of the bearing portion and the face structure of the head thus following the contour above the bearing portion. This gives additional resistance to a force applied to the lower points of the head due to breakage of a shoe.

The rear portion of the brake-head extending between the portions 13 is in the form of a strap 14 integral with the head at its upper end and separated from the head at its lower end by the space 15. Within the lower end of the strap 14 and also within the head, is provided a recess 16 within which is located a lower wedge-member 17 movable with a bolt 19, which bolt extends through the lower end of the strap 14 and accommodates a nut 20. Cooperating with the lower wedge-member 17 is an upper wedge-member 18 normally seated within one of the grooves 11 in the sleeve. As an additional safeguard, the key 21, is provided, extending transversely of the lower wedge-member 17. It will be seen that with the key 21 in place the wedge-member 17 may not be removed a sufficient distance to permit the lowering of the upper wedge-member 18 to clear the groove 11.

It will be seen that upon tightening the nut 20 the wedge-members co-operate to force the upper member against the sleeve, at the same time tightly clamping the strap 14 against the outer surface of the sleeve. The advantages of the split-head and wedge clamping means are thus secured without weakening the brake-head.

I claim:

1. A brake head comprising a face portion and a bearing portion, said bearing portion being of annular form and circumferentially unbroken, a strap integrally connected to said head at one end, wedge means, and a bolt actuating both said wedge means and said strap to clamp said head on a brake beam, substantially as described.

2. In a brake beam, the combination of a bearing sleeve, a brake head having continuous bearing portions coöperating with said sleeve, a strap connected to said head at one end, wedge means, and a bolt acting on said strap and said wedge means where- by to clamp said head on said sleeve, substantially as described.
- 5 CHARLES S. KNAPP.
